UNITED STATES PATENT OFFICE.

WARREN D. SMITH, OF NEW YORK, N. Y.

MACHINE FOR MAKING PACKING.

1,085,948.

Specification of Letters Patent. Patented Feb. 3, 1914.

Application filed October 8, 1912. Serial No. 724,546.

To all whom it may concern:

Be it known that I, WARREN D. SMITH, a citizen of the United States, and a resident of New York, borough of Brooklyn, county of Kings, and State of New York, have invented a certain new and useful Improvement in Machines for Making Packing, of which the following is a full, clear, and exact specification.

10 This invention relates to a class of machines adapted to be employed for making packing to be used especially upon the piston rods, or other parts of various kinds of machinery, or the like.

15 My invention has for its object primarily to provide a form of machine designed to be employed for producing rod packing made of asbestos cloth, or other fabric, or flexible material for use in various parts of 20 machinery, and which is constructed so as to be adapted to form the core of the packing as well as applying thereon a suitable wrapper, thus dispensing with the requirement of making this type of packing by 25 skilled hand-workmanship as is incident to the methods at present in use.

Other objects of the invention are to provide means which serve to form the core of the packing from strips of flexible material; 30 to provide an adjustable shaper whereby cores of various dimensions may be formed; to provide means adapted to apply one or more yielding strips of material, such as rubber to the core; to provide a plurality of freely rotatable rollers, or devices adapted for applying a flexible wrapper upon the core and yielding strip when formed; and to provide a plurality of carriers which serve to deliver the core to the devices for 40 the wrapper to be properly applied thereon.

A further object of the invention is to provide a machine for making packing of simple and efficient construction, and which is susceptible of being made in various sizes.

45 With these and other objects in view, the invention will be hereinafter more particularly described with reference to the accompanying drawings which form a part of this specification, and will then be pointed out 50 in the claims at the end of the description.

In the drawings, Figure 1 is a side elevation, partly fragmentary, of the core forming mechanism employed in my improved machine for making packing. Fig. 2 is a 55 top plan of the core forming mechanism, part of which is fragmentary. Fig. 3 is a

side elevation, of the mechanism of the machine which is employed for applying the wrapper upon the core. Fig. 4 is an enlarged fragmentary side view of part of the core-forming mechanism and wrapping mechanism. Fig. 5 is a side view of the feed rollers of the core mechanism taken on the line II—II of Fig. 1. Fig. 6 is a view of the formers, or folding wheels of the 60 core mechanism taken on the line III—III of Fig. 1. Fig. 7 is a view of the wrapper shaper used in conjunction with the machine, said view being taken on the line IV—IV of Fig. 1. Fig. 8 is a perspective 65 view of one of the devices for applying the wrapper upon the core. Fig. 9 is a side elevation of said device. Fig. 10 is an enlarged detail front elevation, partly in section, of one of the carriers used in conjunction with 70 the machine. Fig. 11 is an enlarged side elevation, partly fragmentary, of the carrier, said view being taken on the line V—V of Fig. 10. Fig. 12 is an enlarged side view of one arm of each of the levers used in the 75 carriers. Fig. 13 is a top plan thereof. Fig. 14 is an enlarged side view of one of the second arms of each of the levers used in the carriers. Fig. 15 is a top plan thereof, and Fig. 16 represents views of the preferred forms of rod packing made by the 80 employment of my machine.

The machine may be supported upon any suitable form of base, or bed-plate, as 11, and consists mainly of a mechanism, or device 12, Figs. 1 and 2, which is adapted to form the core of the rod packing and the core wrapping mechanism, 13, Figs. 2, 3, 8, 9, 10, 11, all of which may be made of any desired shape, or size. Both the core forming mechanism and the core wrapping mechanism are operated simultaneously by a common drive shaft 14 which may be driven by an engine, motor, or any preferred power producing apparatus.

100 The core forming mechanism 12 has two feed rollers 15 and 16 which are held upon shafts 17 and 18, respectively, and these shafts are journaled in a bracket 19 which is supported preferably in a vertical position upon the base-plate 11. One end of each of the shafts 17 and 18 extends somewhat above the bracket 19, and upon each of these extending portions is a gear 20 and 21, both of which are in mesh with a pinion 110 22 rotatably held to the bracket whereby the feed rollers may be revolved in unison.

Power is imparted to the feed rollers 15 and 16 from the drive shaft 14 through the medium of a belt 23 which is guided over a pulley 24 held upon the drive shaft, and also over pulleys 25, 26, 27, 28 which are suitably supported above the mechanism 12. From the pulleys 27 and 28 the belt 23 is guided over a pulley 29 which is held upon the shaft 17 of the roller 15, so that the speed of the drive shaft will be transmitted to the rollers 15 and 16. At alternate spaced intervals upon each of the rollers 15 and 16 are projecting annular flanges, or gripping members 30 and 30' which serve to engage as well as slightly crease the strip of asbestos cloth, or other fabric, or flexible material, as 31, of which the core of the packing is formed, and which is supplied to the machine from a roll, as 32, revolvably mounted upon a bracket 33 supported upon the base plate 11. From the rollers 15 and 16 the material is fed to a shaper 34 which serves to further crease the material longitudinally into plaits whereby it may be readily formed into the core of a square block-like strip, as illustrated. The shaper 34 has a frame 35 composed of vertically disposed spaced standards 36, 37, 38, 39 supported upon a plate 40 which may be provided upon the base plate 11. Through threaded openings provided in the standards 36, 37, 38, 39 are a number of transversely disposed spaced rods 40^a which are also threaded so that said rods may be relatively adjusted. Upon each of the rods 40^a of the standards 36 and 38 are held the ends of longitudinally disposed spaced bars 41, and upon each of the rods 40^a of the standards 37 and 39 are held the ends of a corresponding number of spaced bars 42. Each of the bars 40^a and 41 has an equal number of openings transversely therethrough, and in each of these openings is a freely rotatable wheel 43. As indicated, the standards 36 and 37 are spaced apart for a greater distance than the standards 38 and 39, and the bars are mounted upon all of the standards in a manner so that these bars and the sets of wheels thereof are disposed so as to converge toward the right of the frame 35 whereby the sets of wheels 43 of each of the bars 41 are in spaced overlapping arrangement with relation to the sets of wheels of each of the corresponding bars 41. When the strip of the material for forming the core of the packing is delivered from the feed rollers 15 and 16 to the shaper 34 the material is passed between the sets of wheels 43, and is creased thereby sufficiently to be fed to a core-former, as 44, Figs. 1, 2, 6 which serves to further crease the material into folds of similar widths so as to overlap each other.

The core-former 44 is composed of a bracket 45 which is fastened in a vertical po-

sition upon the base plate 11, and in said bracket are journaled two spaced vertically disposed shafts 46 and 47. Mounted upon each of the shafts 46 and 47 are sets of wheels 48 and 49, and the wheels of each of the shafts are spaced apart so that the wheels of one set are disposed between the wheels of the other set, as shown in Fig. 6. The material of the core as it is creased by the shaper 34 and delivered to the former 44 is guided between the sets of wheels 46 and 47, and is formed thereby into practically a finished shape. Upon the upper part of the shaft 49 is held a bevel gear 50, and meshing with this bevel gear is a bevel gear 51 provided upon the drive shaft 14, in order for rotation to be imparted to the shaft 49 for carrying the core to be delivered between two spaced pressing rollers, as 52 and 53, which are rotatably mounted upon a bracket 54 supported upon the base plate 11. As it is customary to apply upon the material of which this form of packing is made, a coating of adhesive substance, such as rubber cement, the folds of the core when formed by the shaper 34 and the former 44 are adhered together when passed through the pressing rollers 52 and 53. The core thus formed is delivered between two other spaced rollers 55 and 56 which are rotatably held upon a bracket 57 supported upon the base plate 11 in proximity to the bracket 54 of the pressing rollers 52 and 53. The roller 56 is peripherally grooved, as shown at 58, and serves as a means to feed as well as apply upon one surface of the core a strip of yielding material, as 59, which is preferably made of rubber, and this strip is delivered from a roll 60 which is suitably supported above the machine. Upon the base plate 11, and adjacent to the rollers 55 and 56, is a vertically disposed bracket 61 which revolvably carries a roll of flexible material, 62 such as cement coated asbestos cloth, or the like, which is employed as a wrapper upon the square, or rectangular core of the packing. After the core and yielding strip 59 are adhered together, as above described, the finished core is fed between two spaced rollers 63 and 64 of the wrapping mechanism 13 and both of these rollers are rotatably held upon a bracket 65 which is supported upon the base plate 11. The roller 63 is peripherally grooved at 66, as shown in Fig. 7, so as to receive the core of the packing and the wrapper from its roll. The wrapper and the core are fed to the rollers 63 and 64 in a manner whereby the wrapper will be applied, preferably upon three sides of the core, and the partially wrapped packing is then delivered to the device, or mechanism 13 proper for applying thereon one, or more layers of the wrapper. The wrapping mechanism 13 has a frame 67 composed

preferably of four longitudinally disposed bars 68, 68^a, 68^b, 68^c which are spaced apart in substantially a square, or rectangular arrangement, and said frame may be supported in any suitable manner upon the base plate 11.

Disposed at quarter turns upon the square frame 67, and arranged so as to be alternately disposed upon said frame are a plurality of wrapping devices, or groups of adjustable rollers 69 and a plurality of carriers 70. While in the drawings are shown five of the adjustable wrappers 69 and four of the carriers 70 it will be understood that a greater, or less number of these devices may be employed in conjunction with the machine. All of the wrapping devices, or groups of adjustable rollers 69 are alike in formation, and each group of said rollers are arranged upon a supporting plate 71, one of which is fastened upon one side of the frame 67 adjacent to the rollers 63 and 64, and the other four of the supporting plates are connected at spaced intervals to the frame upon each quarter-turn thereof, as illustrated. Through opposite parts of each of the supporting plates 71 are two, or more openings 72 and 73, and midway through the plate is a threaded opening 74. Upon the top of each of the supporting plates 71 is an adjustable bracket 75 having two or more rods 76 and 77 projecting from its underside, and each of said rods is movably directed through one of the openings 72 and 73 of each of the plates so that the bracket may be accurately guided relatively to and from its supporting plate. In order, to conveniently adjust each of the brackets 75, screwed in the threaded opening 74 of each of the supporting plates 71 is a threaded bar 78 having upon one of its ends a hand-wheel 79, and the opposite end of said bar is revolvably connected to the underside of the bracket 75. Extending at a right angle from the top of two of the opposite edges of each of the adjustable brackets 75 are two rigid flanges 80 and 81, and between said flanges in proximity to the ends thereof are two transverse stationary rods 82 and 83. Upon the rods 82 and 83 are two movable bars 84 and 85. The movable bars 84 and 85 are adapted to be adjusted transversely to various distances apart with respect to each other, by the means of a threaded rod 86 which is screwed in threaded openings 87 and 87^a provided centrally through these bars, and said threaded rod is rotated by a hand-wheel 88 held upon one of its ends. Projecting upwardly from the top surface of each of the movable bars 84 and 85 are a series of posts, as 90 and 91, and upon each of said posts is a freely rotatable roller, or idler 92 and 93. When the partially wrapped core is passed through

the rollers 63 and 64 it is delivered to one of the wrapping devices 13, as shown in Fig. 3, and is moved between the series of idlers 92 and 93 of this wrapping device. For the purpose of guiding the wrapper so as to overlap the upper exposed surface 70 of the partially wrapped core, extending upwardly from the top surface of the bar 84 of each of the wrapping devices is a rod 94 having a free threaded end upon which is a thumb screw 95. Also upon the rod 94 is a revolable circular disk 96 having a beveled peripheral edge, as 96^a. Encircling said rod is a spiral spring 97 which is held between a plate 98 upon the upper part of this rod and an anti-friction bearing, as 99, 80 which abuts against the top surface of the disk. The spring 97 thereby serves to hold the disk 96 so as to yieldingly rest upon, or be disposed in close proximity to the top edges of the idlers 92 and 93 while the anti-friction bearing 99 permits free rotation of the disk. As the partially wrapped core is moved between the series of idlers of each of the wrapping devices, the free portion of the wrapper will be engaged by the beveled edge of each of the disks 96, and it will then be guided so as to overlap the surface of the core which is exposed to the underneath surface of each disk. Obviously by arranging the wrapping devices 13 upon quarter-turns of the frame 67, as heretofore mentioned, each surface of the partially wrapped core of the packing will be alternately exposed to the circular disk of one of the devices, and the core will thereby be wrapped with any desired number of layers of the wrapping material. The carriers 70 are also alike in formation, and one of said carriers is disposed between two of the wrapping devices 69. Each of the carriers 70 has a supporting plate 100 which is fastened to the frame 67 of the wrapping mechanism, and the central part of said supporting plate is cut-out to provide a circular opening 101. Rotatable upon an anti-friction bearing, as 102, provided in the opening 101 of each of the supporting plates is an annular gear 103 having its inner peripheral edge toothed, as at 104, and having a bevel toothed face 105. To the face of each of the internal toothed gears 103 which is opposite to its bevel toothed face is fastened a plate 106 and in an opening through each of the plates is journaled a part of the drive shaft 14 of the machine. Upon the drive shaft 14, and adjacent to each of the plates 106 is a gear 107, each of which is in mesh with the inner teeth of one of the annular gears 103 whereby these gears of all of the carriers will be rotated in unison simultaneously with the rotation of the drive shaft. To one face of the supporting plate 100

of each of the carriers are connected the ends of a bracket, or bar 108 which is curved so as to extend somewhat from the opposed face of each of the supporting plates, and in a bearing provided upon each of these brackets is journaled a short shaft 109. Upon one end of each of the short shafts 109 is a bevel pinion 110, each of which is in mesh with the bevel teeth 105 of each of the annular gears 103. On the opposite end of each of the short shafts 109 is a gear 111, and also upon each of these short shafts are pivotally held the central part of the arms 112 and 113, both of which are correspondingly curved and pivoted to the short shaft in a manner to provide substantially X-shaped levers 114. Upon one end of each of the arms 112 and 113 of each of the levers is a stud 115 and 116. Each of the studs 115 carries a revolvable roller 117, and upon each of the studs 116 is a freely rotatable roller 118 which is in alignment with the roller 117. Also upon each of the studs 115 is a pinion 119, each of which is connected to one of the rollers 117 so as to simultaneously rotate the rollers when the pinions are revolved, and each of said pinions is in mesh with one of the gears 111. Thus when the short shafts 109 receive rotation from the annular gears 103 rotation will be imparted to the gears 111, to the pinions 119 and to the rollers 117. The levers 114 serve to force the rollers 117 and 118 of each of the carriers toward each other so that these rollers will convey the core as it is wrapped by one of the wrapping devices to the next wrapping device, as illustrated in Fig. 3. Each of the levers is adapted to permit the rollers 117 and 118 to be adjusted so as to be relatively spaced apart, for a suitable distance whereby the wrapped core may be properly engaged for conveyance from the carriers to the wrapping devices, and for this purpose I employ a screw-rod 120 which is threaded through correspondingly threaded openings 121 provided in each of the arms 112 and 113 of each of the levers. Upon one end of each of the rods 120 is a head 122 which serves to permit said rod to be manually adjusted for spacing the rollers 117 and 118 of each carrier a suitable distance apart, in order to provide for carrying wrapped cores of various dimensions through the machine as well as providing for the variations of the size of the wrapped core while undergoing the different stages of being formed to completion as it is conveyed through the wrapping mechanism.

In the foregoing description I have embodied the preferred form of my invention, but I do not wish to be understood as limiting myself thereto, as I am aware that modifications may be made therein without departing from the principle, or sacrificing

any of the advantages of this invention, therefore I reserve to myself the right to make such changes as fairly fall within the scope thereof.

Having thus described my invention, I claim as new and desire to secure by Letters Patent:—

1. In a machine for making packing, in combination, a base-plate, a drive shaft, a bracket supported upon the base-plate and adapted to carry a rotatable roll of flexible material, means adapted to crease the material longitudinally in the form of plaits, a plurality of rollers adapted to feed the material from its roll to the creasing means, means adapted to impart rotation from the drive shaft to the feed rollers, means adapted to form the material into overlapping folds when delivered from the creasing means, pressing rollers which serve to form the folded material into a square or rectangular core, and a mechanism adapted to wrap the core with layers of flexible material. 75

2. In a machine for making packing, in combination, a base-plate, a drive shaft, a bracket supported upon the base-plate and adapted to carry a rotatable roll of flexible material, means adapted to crease the material longitudinally in the form of plaits, 90 a plurality of rollers adapted to feed the material from its roll to the creasing means, means adapted to impart rotation from the drive shaft to the feed rollers, means adapted to form the material into overlapping folds when delivered from the creasing means, means adapted to impart rotation from the drive shaft to the folding means, pressing rollers which serve to form the material into a square, or rectangular 95 core, means adapted to dispose a strip of yielding material upon one surface of the core, said yielding material being delivered from a rotatable roll upon a suitable support, and a mechanism adapted to wrap the 100 core with layers of flexible material. 105

3. In a machine for making packing, in combination, a base-plate, a drive shaft, a bracket supported upon the base-plate and adapted to rotatably carry a roll of flexible material, a frame upon a suitable support, sets of freely rotatable wheels mounted upon the frame, said wheels serving to crease the material longitudinally in the form of plaits, means adapted to feed the material from its roll to the sets of creasing wheels, means adapted to impart rotation from the drive shaft to the feeding means, means adapted to form the material into overlapping folds when delivered from the creasing wheels, 115 means adapted to impart rotation from the drive shaft to the folding means, pressing rollers which serve to form the material into a square, or rectangular core, means adapted to dispose a strip of yielding material upon 120 the core, and a mechanism adapted to wrap the core with layers of flexible material. 125

130

one surface of the core, said yielding material being delivered from a rotatable roll upon a suitable support, and mechanism adapted to wrap the core with layers of flexible material.

4. In a machine for making packing, in combination, a base-plate, a drive shaft, a bracket supported upon the base-plate and adapted to carry a rotatable roll of flexible

10 material, a frame upon a suitable support, sets of freely rotatable wheels mounted upon the frame, said wheels serving to crease the material longitudinally in the form of plaits, a plurality of rollers adapted to feed

15 the material from its roll to the sets of creasing wheels, means adapted to impart rotation from the drive shaft to the feed rollers, means adapted to form the material into overlapping folds when delivered from

20 the creasing wheels, means adapted to impart rotation from the drive shaft to the folding means, pressing rollers which serve to form the material into a square, or rectangular core, means adapted to dispose a strip

25 of yielding material upon one surface of the core, said yielding material being delivered from a rotatable roll upon a suitable support, and mechanism adapted to wrap the core with layers of flexible material.

30 5. In a machine for making packing, in combination, a base-plate, a drive shaft, a bracket supported upon the base-plate and adapted to carry a rotatable roll of flexible material, means adapted to crease the mate-

35 rial longitudinally in the form of plaits, a plurality of rollers adapted to feed the material from its roll to the creasing means, means adapted to impart rotation from the drive shaft to the feed rollers, a frame upon

40 a suitable support, two spaced shafts journaled in the frame, sets of spaced wheels held upon each of the shafts, said wheels being adapted to form the material into overlapping folds when delivered from the creas-

45 ing means, means adapted to impart rotation from the drive shaft to one of the shafts of the sets of folding wheels, pressing rollers which serve to form the material into a square, or rectangular core, means adapted

50 to dispose a strip of yielding material upon one surface of the core, said yielding material being delivered from a rotatable roll upon a suitable support, and a mechanism adapted to wrap the core with layers of

55 flexible material.

6. In a machine for making packing, in combination, a bed-plate, a drive shaft, a bracket supported upon the base-plate and adapted to carry a rotatable roll of flexible

60 material, a frame upon a suitable support, sets of freely rotatable wheels upon the frame, said wheels serving to crease the material longitudinally in the form of plaits, a plurality of rollers adapted to feed the ma-

65 terial from its roll to the sets of creasing

wheels, means adapted to impart rotation from the drive shaft to the feed rollers, a frame upon a suitable support, two spaced shafts journaled in the frame, sets of spaced wheels held upon each of the shafts, said 70 wheels being adapted to form the material into overlapping folds when delivered from the creasing means, means adapted to impart rotation from the drive shaft to one of the shafts of the sets of folding wheels, 75 pressing rollers which serve to form the material into a square, or rectangular core, means adapted to dispose a strip of yielding material upon one surface of the core, said yielding material being delivered from a 80 rotatable roll upon a suitable support, and a mechanism adapted to wrap the core with layers of flexible material.

7. In a machine for making packing, in combination, a base-plate, a drive shaft, a 85 bracket supported upon the base-plate and adapted to carry a rotatable roll of flexible material, means adapted to crease the material longitudinally in the form of plaits,

means adapted to feed the material from 90 its roll to the creasing means, means adapted to impart rotation from the drive shaft to the feeding means, a frame upon a suitable support, two spaced shafts journaled

in the frame, sets of spaced wheels held 95 upon each of the shafts, said wheels being adapted to form the material into overlapping folds when delivered from the creasing means, means adapted to impart rotation

from the drive shaft to one of the shafts of 100 the sets of folding wheels, pressing rollers which serve to form the material into a square, or rectangular core, means adapted

to dispose a strip of yielding material upon one surface of the core, said yielding material being delivered from a rotatable roll upon a suitable support, and a mechanism adapted to wrap the core with layers of 105

flexible material.

8. In a machine for making packing, in 110 combination, a base-plate, a drive shaft, a bracket supported upon the base-plate and adapted to carry a rotatable roll of flexible material, a frame upon a suitable support,

sets of freely rotatable wheels upon the 115 frame, said wheels serving to crease the material longitudinally in the form of plates, means adapted to feed the material from its roll to the creasing wheels, means

adapted to impart rotation from the drive shaft to the feeding means, a frame upon a suitable support, two spaced shafts journaled in the frame, sets of spaced wheels held upon each of the shafts, said wheels

being adapted to form the material into 120 overlapping folds when delivered from the creasing wheels, means adapted to impart rotation from the drive shaft to one of the shafts of the sets of folding wheels, press-

ing rollers which serve to form the material 130

into a square, or rectangular core, means adapted to dispose a strip of yielding material upon one surface of the core, said yielding material being delivered from a rotatable roll upon a suitable support, and a mechanism adapted to wrap the core with layers of flexible material.

9. In a machine for making packing, in combination, a base-plate, a drive shaft, a bracket supported upon the base-plate and adapted to carry a rotatable roll of flexible material, means adapted to crease the material longitudinally in the form of plaits, a plurality of rollers adapted to feed the material from its roll to the creasing means, means adapted to impart rotation from the drive shaft to the feed rollers, means adapted to form the material into overlapping folds when delivered from the creasing means, means adapted to impart rotation from the drive shaft to the folding means, means serving to form the material into a square, or rectangular core, rollers adapted to dispose a strip of yielding material upon one surface of the core, said yielding material being delivered from a rotatable roll upon a suitable support, and a mechanism adapted to wrap the core with layers of flexible material.

10. In a machine for making packing, in combination, a base-plate, a drive shaft, a bracket supported upon the base-plate and adapted to carry a rotatable roll of flexible material, means adapted to crease the material longitudinally in the form of plaits, a plurality of rollers adapted to feed the material from its roll to the creasing means, means adapted to impart rotation from the drive shaft to the feed rollers, a frame upon a suitable support, two spaced shafts journaled in the frame, sets of spaced wheels held upon each of the shafts, said wheels being adapted to form the material into overlapping folds when delivered from the creasing means, means adapted to impart rotation from the drive shaft to the folding means, means serving to form the material into a square, or rectangular core, rollers adapted to dispose a strip of yielding material upon one surface of the core, said yielding material being delivered from a rotatable roll upon a suitable support, and a mechanism adapted to wrap the core with layers of flexible material.

11. In a machine for making packing, in combination, a base-plate, a drive shaft, a bracket supported upon the base-plate and adapted to carry a rotatable roll of flexible material, a frame upon a suitable support, sets of freely rotatable wheels upon the frame, said wheels serving to crease the material longitudinally in the form of plaits, a plurality of rollers adapted to feed the material from its roll to the sets of creasing wheels, means adapted to impart rotation from the drive shaft to the sets of creasing wheels, means adapted to form the material into overlapping folds when delivered from the creasing wheels, means adapted to impart rotation from the drive shaft to one of the shafts of the sets of folding wheels, means serving to form the material into a square, or rectangular core, rollers adapted to dispose a strip of yielding material upon one

from the drive shaft to the feed rollers, a frame upon a suitable support, two spaced shafts journaled in the frame, sets of spaced wheels held upon each of the shafts, said wheels being adapted to form the material into overlapping folds when delivered from the creasing means, means adapted to impart rotation from the drive shaft to one of the shafts of the sets of folding wheels, means serving to form the material into a square, or rectangular core, rollers adapted to dispose a strip of yielding material upon one surface of the core, said yielding material being delivered from a rotatable roll upon a suitable support, and a mechanism adapted to wrap the core with layers of flexible material.

12. In a machine for making packing, in combination, a base-plate, a drive shaft, a bracket supported upon the base-plate and adapted to carry a rotatable roll of flexible material, means adapted to crease the material longitudinally in the form of plaits, means adapted to feed the material from its roll to the creasing means, means adapted to impart rotation from the drive shaft to the feeding means, a frame upon a suitable support, two spaced shafts journaled in the frame, sets of spaced wheels held upon each of the shafts, said wheels being adapted to form the material into overlapping folds when delivered from the creasing means, means adapted to impart rotation from the drive shaft to one of the shafts of the sets of folding wheels, means serving to form the material into a square, or rectangular core, rollers adapted to dispose a strip of yielding material upon one surface of the core, said yielding material being delivered from a rotatable roll upon a suitable support, and a mechanism adapted to wrap the core with layers of flexible material.

13. In a machine for making packing, in combination, a base-plate, a drive shaft, a bracket supported upon the base-plate and adapted to carry a rotatable roll of flexible material, a frame upon a suitable support, sets of freely rotatable wheels upon the frame, said wheels serving to crease the material longitudinally in the form of plaits, means adapted to feed the material from its roll to the creasing wheels, means adapted to impart rotation from the drive shaft to the feeding means, a frame upon a suitable support, two spaced shafts journaled in the frame, sets of spaced wheels held upon each of the shafts, said wheels being adapted to form the material into overlapping folds when delivered from the creasing wheels, means adapted to impart rotation from the drive shaft to one of the shafts of the sets of folding wheels, means serving to form the material into a square, or rectangular core, rollers adapted to dispose a strip of yielding material upon one

surface of the core, said yielding material being delivered from a rotatable roll upon a suitable support, and a mechanism adapted to wrap the core with layers of flexible material.

14. In a machine for making packing, in combination, a base-plate, a drive shaft, a bracket supported upon the base-plate and adapted to carry a rotatable roll of flexible material, sets of adjustable wheels supported upon the base-plate and disposed in spaced converging arrangement, said sets of wheels being adapted to crease the material longitudinally in the form of plaits, two spaced rollers also supported upon the base-plate and adapted to feed the material from its roll to the sets of adjustable creasing wheels, means adapted to impart rotation from the drive shaft to the feed rollers, means supported upon the base-plate and adapted to form the material into overlapping folds when delivered from the sets of creasing wheels, means adapted to impart rotation from the drive shaft to the folding means, two pressing rollers supported upon the base-plate and serving to form the material into a square, or rectangular core, two rollers also supported upon the base-plate and adapted to dispose a strip of yielding material upon one surface of the core, said yielding material being delivered from a rotatable roll upon a suitable support, and a mechanism adapted to wrap the core with layers of flexible material.

15. In a machine for making packing, in combination, a frame, a supporting plate fastened to the frame, a bracket adjustably held to the supporting plate, sets of alined freely rotatable rollers provided upon the bracket, said sets of rollers being spaced apart so as to permit a partially wrapped square, or rectangular core of flexible material to be guided therebetween, means provided upon the bracket and serving to dispose a layer of the wrapper of the core upon one of the surfaces thereof as the core is transmitted between the sets of rollers, and means adapted to deliver the partially wrapped core to the sets of rollers.

16. In a machine for making packing, in combination, a substantially square frame in cross-section, a plurality of supporting plates, each fastened at spaced intervals upon quarter-turns of the frame, a plurality of brackets, one of which is adjustably held to each of the supporting plates, a plurality of sets of alined rollers, two sets being provided upon each of the brackets and each pair of the sets of rollers being spaced apart so as to permit a partially wrapped square, or rectangular core of flexible material to be guided therebetween, means provided upon each of the brackets and adapted to permit the sets of

rollers thereon to be manually adjusted in relation to each other, means also provided upon each of the brackets and serving to dispose a layer of the wrapper alternately upon each surface of the core thereof as the core is transmitted between each pair of the sets of rollers, and a plurality of carriers, each connected upon quarter-turns of the frame between two of said supporting plates, each of said carriers being adapted to deliver the partially wrapped core to one of the pairs of the sets of said rollers.

17. In a machine for making packing, in combination, a substantially square frame in cross-section, a plurality of supporting plates, each fastened at spaced intervals upon quarter-turns of the frame, a plurality of brackets, one of which is adjustably held to each of the supporting plates, a plurality of sets of alined rollers, two sets being provided upon each of the brackets and each pair of the sets of rollers being spaced so as to permit a partially wrapped square, or rectangular core of flexible material to be guided therebetween, means provided upon each of the brackets and adapted to permit the sets of rollers thereon to be manually adjusted in relation to each other, a plurality of disks, one provided upon each of the brackets and serving to dispose a layer of the wrapper alternately upon each surface of the core thereof as the core is transmitted between each pair of the sets of rollers, and a plurality of carriers, each connected upon quarter-turns of the frame between two of said supporting plates, each of said carriers being adapted to deliver the partially wrapped core to, one of the pairs of the sets of said rollers.

18. In a machine for making packing, in combination, a substantially square frame in cross-section, a plurality of supporting plates, each fastened at spaced intervals upon quarter-turns of the frame, a plurality of brackets, one of which is adjustably held to each of the supporting plates, means adapted to permit each bracket to be manually adjusted to and from each supporting plate, a plurality of sets of alined adjustable rollers, two sets being provided upon each of the brackets and each pair of the sets of rollers being spaced apart so as to permit a partially wrapped square, or rectangular core of flexible material to be guided therebetween, means provided upon each of the brackets and adapted to permit the sets of rollers thereon to be manually adjusted in relation to each other, a plurality of disks, one provided upon each of the brackets and serving to dispose a layer of the wrapper alternately upon each surface of the core thereof as the core is transmitted between each pair of the sets of rollers, and a plurality of carriers, each connected upon quarter-turns of the frame

between two of said supporting plates, each of said carriers being adapted to deliver the partially wrapped core to one of the pairs of the sets of said rollers.

- 5 19. In a machine for making packing, in combination, a substantially square frame in cross-section, a plurality of supporting plates, each fastened at spaced intervals upon a quarter-turn of the frame, and each 10 of said supporting plates having a threaded opening therethrough, a plurality of brackets, one of which is adjustably held to each of the supporting plates, a plurality of threaded rods, each having one of its ends 15 rotatably held to each of the brackets and each of said rods being screwed through the threaded openings of each of the supporting plates, a plurality of sets of aligned rollers, two sets being provided upon each 20 of the brackets and each pair of the sets of rollers being spaced apart so as to permit a partially wrapped square, or rectangular 25 core of flexible material to be guided therebetween, means provided upon each of the the brackets and adapted to permit the sets of rollers thereon to be manually adjusted in relation to each other, a plurality of yielding rotatable disks, one upon each of the brackets and serving to dispose a layer 30 of the wrapper alternately upon each surface of the core thereof as the core is transmitted between each pair of the sets of rollers, and a plurality of carriers, each connected upon quarter-turns of the frame be- 35 tween two of said supporting plates, each of said carriers being adapted to deliver the partially wrapped core to one of the pairs of sets of said rollers.
20. In a machine for making packing, in 40 combination, a substantially square frame in cross-section, a plurality of supporting plates; each fastened at spaced intervals upon a quarter-turn of the frame, a plurality of brackets, one of which is adjust- 45 ably held to each of the supporting plates, a plurality of threaded rods, each having one of its rods rotatably held to each of the brackets and each of said rods being screwed through the threaded opening of 50 each of the supporting plates, a plurality of bars, two of which are movable upon each of the brackets, each pair of said bars being spaced apart, a plurality of sets of rollers, one set being freely rotatable upon 55 each of the movable bars, and each pair of the sets of rollers being adapted to permit a partially wrapped square, or rectangular core of flexible material to be guided there- 60 between, means provided upon each of the brackets and adapted to permit the sets of rollers thereon to be manually adjusted to and from each other, a plurality of yielding rotatable disks, one upon each of the brackets and serving to dispose a layer of 65 the wrapper alternately upon each surface

of the core thereof as the core is transmitted between each part of the sets of rollers, and a plurality of carriers, each connected upon quarter-turns of the frame between two of said supporting plates each of said carriers 70 being adapted to deliver the partially wrapped core to one of the pairs of sets of said rollers.

21. In a machine for making packing, in combination, a substantially square frame 75 in cross-section, a drive shaft, a plurality of supporting plates, each fastened at spaced intervals upon quarter-turns of the frame, a plurality of brackets, one of which is adjustably held to each of the supporting 80 plates, a plurality of sets of aligned rollers, two sets being provided upon each of the brackets and each pair of the sets of rollers being spaced apart so as to permit a partially wrapped square, or rectangular 85 core of flexible material to be guided therebetween, means provided upon each of the brackets and adapted to permit the sets of rollers thereon to be manually adjusted in relation to each other, means also provided 90 upon each of the brackets and serving to dispose a layer of the wrapper alternately upon each surface of the core thereof as the core is transmitted between each pair of the sets of rollers, a plurality of carriers, 95 each connected upon quarter-turns of the frame between two of said supporting plates, all of the carriers being adapted to be operated in unison by the drive shaft and each of said carriers being adapted to de- 100 liver the partially wrapped core to one of the pairs of sets of said rollers, and a mechanism adapted to form a folded square, or rectangular core of flexible material. 105
22. In a machine for making packing, in combination, a substantially square frame in cross-section, a drive shaft, a plurality of supporting plates, each fastened at spaced intervals upon quarter-turns of the frame, a plurality of brackets, one of which is ad- 110 justably held to each of the supporting plates, means adapted to permit each bracket to be manually adjusted to and from each supporting plate, a plurality of sets of aligned adjustable rollers, two sets being provided 115 upon each of the brackets and each pair of the sets of rollers being spaced apart so as to permit a partially wrapped square, or rectangular core of flexible material to be guided therebetween, means provided upon each of the brackets and adapted to permit the sets of rollers thereon to be manually adjusted in relation to each other, a plurality of disks, one provided upon each of the brackets and serving to dispose a layer of the wrapper alternately upon each surface of the core thereof as the core is transmitted between each pair of the sets of rollers, a plurality of carriers, each connected upon quarter-turns of the frame between two of 120 125 130

9
said supporting plates, all of the carriers being adapted to be operated in unison by the drive shaft, and each of said carriers being adapted to deliver the partially wrapped 5 core to one of the pairs of sets of said rollers, and a mechanism adapted to form a folded square, or rectangular core of flexible material.

10 23. In a machine for making packing, in combination, a substantially square frame in cross-section, a drive shaft, a plurality of supporting plates, each fastened at spaced intervals upon quarter-turns of the frame and each of said supporting plates having a 15 threaded opening therethrough, a plurality of brackets, one of which is adjustably held to each of the supporting plates, a plurality of threaded rods, each having one of its ends rotatably held to each of the brackets and 20 each of said rods being screwed through the threaded opening of each of the supporting plates, a plurality of sets of alined rollers, two sets being provided upon each of the brackets and each pair of the sets of rollers 25 being spaced apart so as to permit a partially wrapped square, or rectangular core of flexible material to be guided therebetween, means provided upon each of the brackets and adapted to permit the sets of 30 rollers thereon to be manually adjusted in relation to each other, a plurality of yielding rotatable disks, one upon each of the brackets and serving to dispose a layer of the wrapper alternately upon each surface of the 35 core thereof as the core is transmitted between each pair of the sets of rollers, a plurality of carriers each connected upon quarter-turns of the frame between two of said supporting plates, all of the carriers being adapted 40 to be operated in unison by the drive shaft, and each of said carriers being adapted to deliver the partially wrapped core to one of the pairs of sets of said rollers, and a mechanism adapted to form a folded square, or 45 rectangular core of flexible material and partially wrap said core with a layer of flexible material.

50 24. In a machine for making packing, in combination, a substantially square frame in cross-section, a drive shaft, a plurality of supporting plates, each fastened at spaced intervals upon quarter-turns of the frame, a plurality of brackets, one of which is adjustably held to each of the supporting 55 plates, a plurality of threaded rods, each having one of its ends rotatably held to each of the brackets and each of said rods being screwed through the threaded opening of each of the supporting plates, a plurality of bars, two of which are movable upon each 60 of the brackets, each pair of said bars being spaced apart, a plurality of sets of rollers, one set being freely rotatable upon each of the movable bars, and each pair of the sets 65 of rollers being spaced apart so as to permit

a partially wrapped square, or rectangular core of flexible material to be guided therebetween, means provided upon each of the brackets and adapted to permit the sets of rollers thereon to be manually adjusted to and from each other, a plurality of yielding rotatable disks, one upon each of the brackets and serving to dispose a layer of the wrapper alternately upon each surface of the core thereof as the core is transmitted between each pair of the sets of rollers, a plurality of carriers each connected upon quarter-turns of the frame between two of said supporting plates, all of the carriers being adapted to be operated in unison by the drive shaft, and each of said carriers being adapted to deliver the partially wrapped core to one of the pairs of sets of said rollers, and a mechanism adapted to form a folded square, or rectangular core of flexible material and partially wrap said core with a layer of flexible material.

70 25. In a machine for making packing, in combination, a frame, a drive shaft journaled in the frame, a plurality of supporting plates fastened at spaced intervals upon the frame, a plurality of annular gears, one of which is rotatable upon each of the supporting plates, and each of said annular gears having teeth upon its inner peripheral edge 75 and having bevel teeth upon one of its faces, a plurality of gears held upon the drive shaft, one of which is in mesh with the inner teeth of each of the annular gears whereby said annular gears may be rotated in 80 unison, a plurality of short shafts, a plurality of bevel gears, each held upon one end of each of the short shafts, and one of said bevel gears being in mesh with the bevel teeth of each of the annular gears, a plurality of gears, one of which is held upon the opposite end of each of the short shafts, a plurality of pairs of levers, each pair being pivoted upon one of the short shafts in substantially an X-shape, a plurality of studs, 85 one projecting from the similar face of each of the levers, a plurality of pinions, one held upon one of the short studs of each pair of levers, and meshing with the gear upon one of the short shafts, a plurality of rollers, one being freely rotatable upon the short stud of the second lever of each pair, means adapted to adjustably hold the arms of each of the bell-crank levers so that the rollers thereof will be suitably spaced apart for carrying a 90 core of flexible material therebetween, and a plurality of wrapping devices supported at spaced intervals upon the frame, each of said devices being adapted to dispose upon the core a layer of flexible wrapping material.

95 26. In a machine for making packing, in combination, a frame, a drive shaft journaled in the frame, a plurality of supporting plates fastened at spaced intervals upon the frame, a plurality of annular gears, one of 100

which is rotatable upon each of the supporting plates, and each of said annular gears having teeth upon its inner peripheral edge and having bevel teeth upon one of its faces, 5 a plurality of gears held upon the drive shaft, one of which is in mesh with the inner teeth of each of the annular gears whereby said annular gears may be rotated in unison, a plurality of short shafts, a plurality of 10 bevel gears, one held upon one end of each of the short shafts, and one of said bevel gears being in mesh with the bevel teeth of each of the annular gears, a plurality of gears, one of which is held upon the opposite end 15 of each of the short shafts, a plurality of pairs of levers, each pair being pivoted upon one of the short shafts in substantially an X-shape, a plurality of studs, one projecting from the similar face of each of the 20 levers, a plurality of pinions, one held upon one of the short studs of each pair of levers, and meshing with the gear upon one of the short shafts, a plurality of rollers, one being freely rotatable upon the short studs of the 25 second lever of each pair, a screw adapted to adjustably hold the levers of each pair so that the rollers thereof will be suitably spaced apart for carrying a core of flexible material therebetween, and a plurality of 30 wrapping devices supported at spaced intervals upon the frame, each of said devices being adapted to dispose upon the core a layer of flexible wrapping material.

27. In a machine for making packing, in combination, a frame, a drive shaft journaled in the frame, a plurality of supporting plates fastened at spaced intervals upon the frame, a plurality of annular gears, one of which is rotatable upon each of the supporting plates, and each of said annular gears having teeth upon its peripheral edge and having bevel teeth upon one of its faces, a plurality of gears held upon the drive shaft, one of which is in mesh with the inner 45 teeth of each of the annular gears whereby said annular gears may be rotated in unison, a plurality of short shafts, a plurality of bevel gears; each held upon one end of each of the short shafts, and one of said bevel 50 gears being in mesh with the bevel teeth of each of the annular gears, a plurality of pairs of freely rotatable rollers, each pair being provided upon one of the supporting plates, means adapted to adjustably hold 55 each pair of the rollers so as to be suitably spaced apart for carrying a core of flexible material therebetween, and a plurality of wrapping devices supported at spaced intervals upon the frame, each of said devices 60 being adapted to dispose upon the core a layer of flexible wrapping material.

28. In a machine for making packing, in combination, a frame, a drive shaft journaled in the frame, a plurality of supporting plates fastened at spaced intervals upon

the frame, a plurality of annular gears, one of which is rotatable upon each of the supporting plates, and each of said annular gears having teeth upon its inner peripheral edge and having bevel teeth upon one of its faces, a plurality of gears held upon the drive shaft, one of which is in mesh with the inner teeth of each of the annular gears whereby said annular gears may be rotated in unison, a plurality of short shafts, a plurality of bevel gears, each held upon one end of each of the short shafts, and one of said bevel gears being in mesh with the bevel teeth of each of the annular gears, a plurality of gears, one of which is held upon the opposite end of each of the short shafts, a plurality of pairs of levers, each pair being pivoted upon one of the short shafts in substantially an X-shape, a plurality of studs, one projecting from the similar face of each of the levers, a plurality of pinions, one held upon one of the short studs of each pair of levers, and meshing with the gear upon one of the short shafts, a plurality of rollers, one being freely rotatable upon the short stud of the second lever of each pair, means adapted to adjustably hold the arms of each of the bell-crank levers so that the rollers thereof will be suitably spaced apart for carrying a core of flexible material therebetween, a plurality of wrapping devices supported at spaced intervals upon the frame, each of said devices being adapted to dispose upon the core a layer of flexible wrapping material, and means adapted to form the core of flexible material.

29. In a machine for making packing, in combination, a frame, a drive shaft journaled in the frame, a plurality of supporting plates fastened at spaced intervals upon the frame, a plurality of annular gears, one of which is rotatable upon each of the supporting plates, and each of said annular gears having teeth upon its inner peripheral edge and having bevel teeth upon one of its faces, a plurality of gears held upon the drive shaft, one of which is in mesh with the inner teeth of each of the annular gears whereby said annular gears may be rotated in unison, a plurality of short shafts, a plurality of bevel gears, one held upon one end of each of the short shafts, and one of said gears being in mesh with the bevel teeth of each of the annular gears, a plurality of gears, one of which is held upon the opposite end of each of the short shafts, a plurality of pairs of levers, each pair being pivoted upon one of the short shafts in substantially an X-shape, a plurality of studs, one projecting from the similar face of each of the levers, a plurality of pinions, one held upon one of the short studs of each pair of levers, and meshing with the gear upon one of the short shafts, a plurality of rollers, one being freely rotatable upon the short stud of

the second lever of each pair; a screw adapted to adjustably hold the levers of each pair so that the rollers thereof will be suitably spaced apart for carrying a core of flexible material therebetween, a plurality of wrapping devices supported at spaced intervals upon the frame, each of said devices being adapted to dispose upon the core a layer of flexible wrapping material, and means

10 adapted to form the core of flexible material.

30. In a machine for making packing, in combination, a drive shaft journaled in the frame, a plurality of supporting plates fastened at spaced intervals upon the frame, a 15 plurality of annular gears, one of which is rotatable upon each of the supporting plates, and each of said annular gears having teeth upon its peripheral edge and having bevel teeth upon one of its faces, a plurality of 20 gears held upon the drive shaft, one of which is in mesh with the inner teeth of each of the annular gears whereby said annular gears may be rotated in unison, a plurality of short shafts, a plurality of bevel

gears, each held upon one end of each of 25 the short shafts, and one of said bevel gears being in mesh with the bevel teeth of each of the annular gears, a plurality of brackets, one fastened to each of the supporting plates, a plurality of pairs of freely rotatable rollers, each pair being provided upon one of the brackets, means adapted to adjustably hold each pair of the rollers so as to be suitably spaced apart for carrying a core of flexible material, a plurality of wrapping devices supported at spaced intervals upon the frame, each of said devices being adapted to dispose upon the core a layer of flexible wrapping material, and means 30 adapted to form the core of flexible material. 35

This specification signed and witnessed this seventh day of October A. D. 1912.
